(57) **CLAIM**

I claim the ornamental design for a teat, as shown and described.

DESCRIPTION

FIG. 1 is a top, front, left perspective view of a teat, showing my new design;

FIG. 2 is a front cross-sectional elevation view, taken in the direction of line 2-2 of FIG. 1; and,

FIG. 3 is a left side cross-sectional elevation view, taken in the direction of line 3-3 of FIG. 1.

The broken lines depict portions of the teat that form no part of the claimed design.

The areas shaded with stippling in FIG. 1 are indicative of a difference in texture in relation to non-stippled areas of the design.
